UNITED STATES PATENT OFFICE

114,752

DESIGN FOR A STICK FOR FROZEN CONFECTIONERY

Anthony De Laurentis, Chicago, Ill.

Application February 20, 1939, Serial No. 83,109

Term of patent 14 years

To all whom it may concern:

Be it known that I, Anthony De Laurentis, a citizen of the United States, residing in the city of Chicago, in the county of Cook and State of Illinois, have invented a new, original, and ornamental Design for a Stick for Frozen Confectionery, of which the following is a specification, reference being had to the accompanying drawing, forming a part thereof, and in which

Fig. 1 is a face view of a stick for frozen confectionery showing my new design;

Fig. 2 an edge view;
Fig. 3 a top plan view;
Fig. 4 a section taken on line 4—4 of Fig. 1; and
Fig. 5 a section taken on line 5—5 of Fig. 1.

I claim:

The ornamental design for a stick for frozen confectionery, as shown.

ANTHONY DE LAURENTIS.
